His Attorney

UNITED STATES PATENT OFFICE

HENRY W. WOLFF, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

HIGHWAY-CROSSING-PROTECTION APPARATUS

Application filed January 31, 1929. Serial No. 336,441.

My invention relates to apparatus for the protection of crossings of highways and railways, and particularly to crossing protection apparatus of the type involving light signals.

One feature of my invention is the provision of a signal comprising a plurality of electric lamps arranged in a circle, and means for successively lighting such lamps to give an indication which is highly distinctive and arrestive in character.

I will describe one form of apparatus embodying my invention, and will then point out the novel features thereof in claims.

In the accompanying drawing, Fig. 1 is a diagrammatic view showing one form of crossing protection apparatus embodying my invention. Fig. 2 is a developed view of the drum 2 forming part of the circuit controller C shown in Fig. 1.

Similar reference characters refer to similar parts in each of the views.

Referring first to Fig. 1, the reference character S designates a signal comprising a plurality of main lamps L arranged in a circle, with an auxiliary lamp X^L located at the center of the circle. As here shown, each main lamp L is diametrically opposite another main lamp L, and the two lamps of each diametrically opposed pair are provided with the same exponent. The lamps are all mounted on a background 5 in any suitable manner, but the mechanical construction of the signal is not illustrated in the drawing for the reason that it forms no part of my present invention.

The lamps L in the signal S are provided with circuits which are governed by a circuit controller C. This circuit controller comprises a cylindrical drum 2 of insulating material provided with contact segments 3 which co-operate with fixed contact fingers 4. The drum 2 is at times rotated by an electric motor M, which is controlled in a manner explained hereinafter. As illustrated more fully in Fig. 2, the contact segments are progressively disposed around the surface of the drum 2, so that as this drum rotates the pairs of contact fingers 4^a, 4^b, 4^c and 4^d are successively bridged.

The motor M and the lamps of signal S are controlled by a track relay R connected with the rails of a track section T and normally energized by a track battery B^a. The relay R is provided with two back contacts 6 and 7, which are normally open, but which become closed when the relay R becomes de-energized due to the entrance of a train into section T.

The operation of the apparatus is as follows: Assuming that track section T is unoccupied, relay R is energized so that contacts 6 and 7 are open, motor M is at rest, and all of the lamps of signal S is extinguished. If, now, a train enters section T, track relay R will become de-energized, thereby closing both of its contacts 6 and 7. The auxiliary lamp X^L will then be lighted by virtue of a circuit which passes from battery B^a, through back contact 6 of relay R and the lamp X^L to battery B^a. This lamp will therefore remain lighted as long as relay R remains de-energized. Main lamps L^a will also become lighted by virtue of a circuit which passes from battery B^a, through relay contact 6, contact fingers 4^a, segment 3^a, and lamps L^a to battery B^a. Motor M will also become energized by virtue of a circuit which includes a battery B^b and contact 7, so that the drum 2 of circuit controller C will rotate in the direction indicated by the arrow in Fig. 2. At the moment that segment 3^a leaves the contact fingers 4^a, segment 3^b will bridge contact fingers 4^b, so that lamps L^a will become extinguished and the two lamps L^b will become lighted, the circuit for these lamps being obvious from the drawing.

Upon further travel of the drum 2, segment 3^b will leave the contact fingers 4^b, and segment 3^c will simultaneously engage contact fingers 4^c; lamps L^b will then be extinguished and lamps L^c will be lighted. Upon further travel of the drum 2, segment 3^c will leave contact fingers 4^c, and segment 3^d will engage contact fingers 4^d; lamps L^c will then become extinguished and lamps L^d will become lighted. In similar manner, the several pairs of diametrically opposed lamps will be successively lighted as long as motor M continues to rotate, and so the signal will

give the optical illusion of a revolving row of three lights thereby providing an indication which is unique and highly arrestive in character.

5 Although I have herein shown and described only one form of apparatus embodying my invention, it is understood that various changes and modifications may be made therein within the scope of the appended 10 claims without departing from the spirit and scope of my invention.

Having thus described my invention, what I claim is:

15 1. Apparatus for highway crossing protection comprising, a signal having electric lamps arranged in a circle, each lamp being diametrically opposite another lamp, and means for successively lighting the diametrically opposite pairs of lamps.

20 2. Apparatus for highway crossing protection comprising a signal having a group of main lamps arranged in a circle, each lamp being diametrically opposite another lamp, an auxiliary lamp located at the center of 25 such circle, means for successively lighting the diametrically opposite pairs of main lamps, and means for lighting said auxiliary lamp while said first means is in operation.

30 3. Apparatus for highway crossing protection comprising a signal having electric lamps arranged in a circle, each lamp being diametrically opposite another lamp, a circuit controller having a plurality of contacts one for each diametrically opposed pair of 35 lamps, a circuit for each such pair of lamps including the associated contact of said circuit controller, and means for operating said circuit controller to close its contacts serially and thereby to successively light the diametrically opposite pairs of lamps.

40 In testimony whereof I affix my signature.
HENRY W. WOLFF.
